UNITED STATES PATENT OFFICE.

RICHARD W. OSWALD, OF PITTSBURGH, PENNSYLVANIA.

METALLIC TIE AND RAIL-FASTENER.

1,091,530.

Specification of Letters Patent. Patented Mar. 31, 1914.

Application filed March 8, 1913. Serial No. 753,030.

To all whom it may concern:

Be it known that I, RICHARD W. OSWALD, a citizen of the United States, residing at Pittsburgh, in the county of Allegheny and

5 State of Pennsylvania, have invented a new and useful Metallic Tie and Rail-Fastener, of which the following is a specification.

The present invention relates to improvements in metallic ties and rail fasteners, the 10 primary object of the present invention being the provision of a tie provided with a longitudinal groove in the rail base receiving face thereof, for the reception of a malleable fastening means to embrace the opposite edges of a rail base to lock the same against upward movement relative to the tie, there being placed to bridge the groove below the base of the rail a tie plate, which is fastened to the tie, such base plate forming 15 a means to prevent the transverse creeping of the rail while the malleable fastening provides a means as before stated to prevent the upward movement of the rail.

The present invention is applicable to a 20 hollow channeled tie or a tie with a central longitudinal web, it being essential however, that a longitudinal groove be provided in the rail base receiving plate adjacent the point for the reception of the rail 25 base.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed without 35 departing from the spirit of the invention.

In the drawings—Figure 1 is a cross section taken through a rail with the same applied to a metallic tie by the present form of invention. Fig. 2 is a side elevation of 40 the rail and end view of the tie with the present fastener. Figs. 3 and 4 are detail views of the tie plate. Figs. 5 and 6 are detail views of the malleable detachable fastening means. Fig. 7 is a view similar to 45 Fig. 1 showing a channel tie with a modified form of fastening. Fig. 8 is an end view of the tie and side elevation of the rail attached by the fastening shown in Fig. 7. Fig. 9 is an enlarged detail view showing 50 a modified form of tie plate used in connection with the tie, as shown in Figs. 7 and 8.

Fig. 10 is an end view of the tie plate, as shown in Fig. 9. Fig. 11 is a view similar to Fig. 1, showing the present invention as applied to a tie composed of two longitudinally spaced members. Fig. 12 is an end view thereof. Fig. 13 is a top plan view of a portion of the tie and rail, and Fig. 14 is a top plan view of the tie and fastener without the rail.

Referring to the drawings, and more particularly to Figs. 1 through 6, the numeral 1 designates the base of the tie, which is provided with an upstanding centrally disposed longitudinal web 2, which carries the 70 rail receiving head 3, having the oppositely extending plates 4, there being provided longitudinally of the tie or at the rail base receiving portion thereof a groove 5, the purpose of which will presently appear. 75

Placed upon the portions 4 of the tie and bridging the groove 5 of the tie, is the tie plate 5', the detail structure of which is clearly shown in Figs. 3 and 4. This plate is provided with the spaced lugs 6, two at 80 each end thereof, and each plate is secured by means of rivets 7 passing through the apertures of the lugs 6 and the web portion 4 of the tie. By this means the tie plate is secured at the rail bearing portion of the 85 tie, as clearly illustrated in Figs. 1 and 2. Upon the upper face of the plate 5' are formed the parallel rail base engaging and limiting lugs 8, the recessed portions between the lugs 6 being cut away, as at 9, beyond the inner edges of the respective lugs 8.

The base 10 of the rail 11 is disposed upon the body of the plate 5', and its adjacent edges between the respective lugs 8, while in order to secure the rail downwardly upon 95 the plate a fastening member 12 provided with a hooked driving end 13 is placed below the plate through the groove 5, the opposite terminal being bent up as at 14 to engage the opposite edge of the rail base 10 100 and thus securely clamp the hooked end portion 13 in engagement at the opposite side of the rail base. Thus the member 12 securely fastens the rail base downwardly and upon the tie plate 5', while the rivets 7 105 securely fasten the plate to the tie. By this means the rail is held against sidewise sliding or tilting movement, yet is permitted the necessary longitudinal movement due to contraction and expansion.

In the form shown in Figs. 7 through 10, a hollow channeled tie 15 is employed, the

same being provided with the parallel flanges 16 and the longitudinally disposed central groove 17, as clearly shown in Fig. 8. This tie is of well known construction, 5 and is merely shown to show the application of the present fastener for the rail thereto.

The tie plate 18 in the present instance, slightly deviates from the tie plate 5', the same being provided, in addition to the aper- 10 tured lug 21, which corresponds to the lugs 6 of the before mentioned tie plate, with an upstanding hooked portion 19, which is formed from the metal cut from between two of the lugs 21 at one side of the plate, 15 and thus forming an auxiliary gripping means for engaging the base of the rail 23 at one side, so that the fastening member 12', may be positioned, as clearly shown in Figs. 7 and 8, to present its hooked head 13' 20 at one side with the malleable terminal 14' bent to surround and engage the hook 19 of the tie plate. By this means the tie plate 18 which is riveted as at 22 to the tie 15, in combination with the fastening device 12', 25 holds the rail in proper assembled position relatively to the tie. In the form of tie plate used in Figs. 9 and 10, additional lugs 20 are provided which correspond to the lugs 8 of the tie plate 5'.

30 In the form of tie shown in Figs. 1 and 2, the lower longitudinal groove 1' formed in the under side of base 1 thereof is provided to prevent the tie from creeping while the peculiar formation of the web 2 and its head 3, will permit of the rolling of the tie in a rolling mill, and will produce an exceedingly resilient tie as compared with an ordinary I-beam tie.

In Figs. 11 through 14, the tie consists of 40 the channeled members 24—24', connected below at the rail bearing portion with the plate 25, thus providing a longitudinal space between the members. A rail receiving plate 28 is connected to the upper flanges of the 45 members 24—24' by rivets 29, and the fastening member 12^a with its head 13^a and bent up end 14^a is passed below the plate 28 and in the space 26 between the members 24—24'. Thus the fastener 12^a embraces the 50 base 10' of the rail and is held in place similarly to the fastener 12.

What is claimed is:

1. The combination with a tie having a longitudinal space in the rail bearing face 55 thereof, of a rail fastener including a plate secured to the rail bearing face of the tie

and spanning the space, and a malleable hooked head spike disposed in the space below the plate with its terminal beyond the rail base receiving portion of the plate, the 60 insert terminal being bent inwardly to engage the rail base and clamp the hooked head upon the opposite side of the rail base while the body of the spike is below and parallel to the under surface of the base of 65 the rail.

2. The combination with a tie having a longitudinal space in the rail bearing face thereof, of a rail fastener including a plate secured to the rail bearing face of the tie 70 and spanning the space, and a malleable hooked head spike disposed in the space below the plate with its terminal beyond the rail base receiving portion of the plate, the 75 insert terminal being bent inwardly to engage the rail base and clamp the hooked head upon the opposite side of the rail base, said plate being provided with parallel rail base limiting lugs on the upper face thereof. 80

3. The combination with a tie having a longitudinal space in the rail bearing face thereof, of a rail fastener including a plate secured to the rail bearing face of the tie and spanning the space, and a malleable member 85 of greater length than the width of the base of the rail fitted in the space below the plate and having its terminals hooked to engage opposite sides of the rail base, said plate being provided with parallel rail base limit- 90 ing lugs on the upper face thereof.

4. The combination with a metal tie having a longitudinal space in the rail bearing face thereof, of a rail fastener including a plate having two oppositely disposed spaced 95 lugs at each end, means for securing said lugs to the rail bearing face of the tie, the body of the plate spanning the space in the tie, and a malleable member of greater length than the width of the base of a rail 100 inserted in the space below the plate and having its terminals hooked to engage opposite sides of the rail base, said plate being provided with parallel rail base limiting lugs on the upper face thereof. 105

In testimony that I claim the foregoing as my own, I have hereto affixed my signature in the presence of two witnesses.

RICHARD W. OSWALD.
